UNITED STATES PATENT OFFICE.

SUREN MATOSIAN, OF LOS ANGELES, CALIFORNIA.

DESIGN FOR A DRAPERY-ROD END.

Application filed January 16, 1929. Serial No. 29,630. Term of patent 3½ years.

To all whom it may concern:

Be it known that I, SUREN MATOSIAN, a subject of the Government of Armenia, under the protectorate of France, residing at Los Angeles, in the county of Los Angeles and State of California, have invented a new, original, and ornamental Design for Drapery-Rod End, of which the following is a

specification, reference being had to the accompanying drawing, forming part thereof.

The figure in the drawing is a perspective view of a drapery rod end showing my design.

I claim:

The ornamental design for a drapery rod end as shown.

SUREN MATOSIAN.
